(57) **CLAIM**

The ornamental design for a pizza slicing device, substantially as shown.

DESCRIPTION

FIG. 1 is a perspective view of a pizza slicing device, showing my new design;

FIG. 2 is a left side elevation of the slicer of FIG. 1;

FIG. 3 is a top plan view of the slicer of FIG. 1;

FIG. 4 is a bottom plan view of the slicer of FIG. 1;

FIG. 5 is a right side elevation of the slicer of FIG. 1;

FIG. 6 is a front side elevation of the slicer of FIG. 1; and,

FIG. 7 is a rear side elevation of the slicer of FIG. 1.
